UNITED STATES PATENT OFFICE

2,654,528

ACCELERATOR AND DIFFUSING NOZZLE
FOR VENTILATING STACKS

Ben Cones, Indianapolis, Ind.

Application October 31, 1951, Serial No. 254,169

3 Claims. (Cl. 230—96)

1

This invention relates to a nozzle having for its primary purpose the acceleration of a column of air within a stack and the intermixing therewith of fresh air or warmed air in such manner that the resultant flow will be entirely silent.

A further important object of the invention is to provide a very positive acceleration of the air movement within the stack during the intermixing operation so that a positive intermixing relation may be had between the stack air and air introduced through an additional pipe or flue.

The invention is to be applied to a heating and ventilating system wherein there is normally supplied to that system a flow of warm air through a duct or pipe, and that warm air is entered into a natural draft flue, the flue or stack taking in air from an opening near the floor of the room to be heated and ventilated, and discharging the air through that flue opening above the position of the nozzle so that the intermixing air from the room and from the pipe may be introduced into the room in very definite proportions. By use of the nozzle, the flow of the air from the room into the flue and thereout is positively induced.

A further primary object of the invention is to provide an extremely simplified structure which may be produced at a very low cost of production and which may be inserted and fixed in or across the end of the warm air pipe within the flue itself, and thereafter require no further adjustment or regulation of any kind whatsoever.

These and many other objects and advantages of the invention will become apparent to those versed in the art in the following description of one particular form of the invention, as illustrated in the accompanying drawing, in which

Fig. 1 is a view in side elevation of the nozzle;

Fig. 2 is a view in vertical cross section through a flue and warm air pipe to which the invention is applied; and

Fig. 3 is a view in transverse section on the line 3—3 in Fig. 1.

I form a nozzle generally designated by the numeral 10, and this nozzle may be made in one piece, or it may be made in two parts, as illustrated in the accompanying drawing.

A substantially hemispherical dome 11 is formed out of metal to have a centrally disposed upwardly turned nipple 12 through which there is an opening 33. A conical base portion 13 is formed to have a base which will have an outside diameter equal to the outside diameter of the base of the part 11 so that when the dome 11

2

is placed over the base of the cone 13, the cone 13 being inverted, there will be a smooth external junction between the surfaces of the cone and of the dome 11. The dome 11 and the cone 13 are held in this abutting arrangement by any suitable means, herein shown as by the screws 14 and 15 passing freely through the dome 11 and screw threadedly engaging in the cone 13 as indicated in Fig. 2. The apex end of the cone 13 terminates in an opening 16, the margin of which lies in a plane at right angles to the vertical center line through the cone.

The opening 33 is made to be slightly larger than is the opening 16. For example, in a nozzle 10 having a major diameter of substantially five inches, a cone height of four and one half inches, a dome plus nipple height of three and one half inches, the lower hole 16 would have a diameter of fifteen-sixteenths and the diameter of the hole 13 would be seven-eighths. These figures are given for proportions only and not as limiting factors of the size of the nozzle 10, since that nozzle may be varied to meet the conditions of air flows required.

Arranged around the face of the cone 13 are a plurality of fins 17, each having a foot 18 as a means for mounting the nozzle 10 in the upper end of the warm air pipe 19. The feet 18 fit against the inside face of the wall of the pipe 19 and are secured by any suitable means, such as by the rivets 20.

As indicated in Fig. 2, the cone 13 is pointed downwardly into the pipe 19, and the lower end which carries the opening 16 must be spaced somewhat below the upper rim 21 of the pipe 19. This spacing must be at least one-fourth of an inch. The nozzle 10 by reason of the positioning effect of the fins 17 mount the nozzle 10 axially of the pipe 19.

The pipe 19, being the warm air conductor, is mounted centrally within a flue 22 which is to convey air from and back into a room. That is, there is space provided around the external side of the pipe 19, completely circumferentially therearound for air to travel between the pipe 19 and the flue 22.

Operation

Assuming that warm air is being forced through the pipe 19 to discharge upwardly over the rim 21, this air will come into contact by a measure volume thereof against the upwardly and outwardly flaring wall of the cone 13 so that the air coming from that pipe 19 is tended to be deflected outwardly toward the wall of the flue

22. This action will tend to set up an ejector action within the flue 22 tending to pull air from the lower space 23 around the pipe 19 upwardly to move along with that air coming out of the pipe 19 and around the cone 13 to above the dome 11.

Now if the nozzle 10 did nothing further than that, the upward air flow would be considerably retarded because there would be eddy currents produced immediately above the dome 11, without a sufficient tendency to carry the air on up in the flue 22 as is required.

Air in part coming up the pipe 19 will enter through the hole 16 into the interior space 24 within the nozzle 10, wherein the warm air tends to expand. In this expanding action, the air tends to reduce its temperature somewhat, and thus a bigger volume of air may be induced to flow through the opening 16 to enter into the space 24, and finally this air being under the pressure induced by the pipe 19 will tend to escape through the upper opening 33.

Air escaping from the opening 33 will fill in the void normally existing above the dome 11, and prevent the formation of eddy currents therearound so that the flow of the air from around the outside of the cone 13 and past the dome 11 becomes a straight line flow with a thorough intermixing of the air coming up from the space 23 with the air coming out of the pipe 19 around the outside of the cone 13 and also with that portion of the air which has been proportioned to flow out through the top opening 33.

Now in all of this flowing action, the air is so controlled that there is no high velocity flow across thin or knife edge surfaces which would tend to produce a noise quite objectionable to the occupants of the room into which the air is to be flowed. To the contrary, the air is expanded from the end of the pipe 19 over the rim 21 and also into the space 24 of the nozzle 10 forming a sound trap during the expansion of the air therein and escape through the hole 33.

A differential in sizes of the holes 33 and 16 contributes greatly to the resultant effect.

It is to be noted that in Figs. 1 and 2, the nipple 12 is shown as merging with a smooth flowing curved surface out of the hemispherical surface of the dome 11, and the top edge of this nipple 12 at a distance above the normal top curvature of the dome 11 not to exceed five-eighths of an inch. This dimension is in accordance with the dimensions above given.

Therefore it is to be seen that I have produced an exceedingly simple structure with no moving parts. The only moving part in conjunction with the entire structure would be a damper 25 carried within the pipe 19 so as to control the volume or rather velocity of the air flowing through that pipe 19. Normally the resultant rate of flow of the air above the nozzle 10 would be in the range of from one thousand five hundred to two thousand feet per minute.

While I have shown the invention and described it in the one particular form, it is obvious that structural variations may be employed without departing from the spirit of the invention, and I therefore do not desire to be limited to that precise form beyond the limitations which may be imposed by the following claims.

I claim:

1. The combination of an air flue; a supply

air pipe discharging by an open end within the air flue in a direction longitudinally and axially of the flue, of a nozzle centered over said pipe end comprising a hollow lower, inverted cone section and an upper substantially hemispherical hollow section merging out of the cone section, said lower and upper sections defining a correspondingly shaped chamber therewithin entirely closed by the side walls of the cone section and said hollow section, each of said sections having an opening in their respective lower and upper ends centered on the longitudinal center line of said pipe; and means fixing the lower end of said cone section in a circumferential spacing from the margin of said pipe opening; and said cone section lower end opening being spaced within said pipe below said pipe open end margin.

2. The combination of an air flue; a supply air pipe discharging by an open end within the air flue in a direction longitudinally and axially of the flue, of a nozzle centered over said pipe end comprising a hollow lower, inverted cone section and an upper substantially hemispherical hollow section merging out of the cone section, said lower and upper sections defining a correspondingly shaped chamber therewithin entirely closed by the side walls of the cone section and said hollow section, each of said sections having an opening in their respective lower and upper ends centered on the longitudinal center line of said pipe; and means fixing the lower end of said cone section in a circumferential spacing from the margin of said pipe opening; and said cone section lower end opening being spaced within said pipe below said pipe open end margin; said cone section opening being smaller in diameter than said opening of said hemispherical section.

3. The combination of an air flue; a supply air pipe discharging by an open end within the air flue in a direction longitudinally and axially of the flue, of a nozzle centered over said pipe end comprising a hollow lower, inverted cone section and an upper substantially hemispherical hollow section merging out of the cone section, said lower and upper sections defining a correspondingly shaped chamber therewithin entirely closed by the side walls of the cone section and said hollow section, each of said sections having an opening in their respective lower and upper ends centered on the longitudinal center line of said pipe; and means fixing the lower end of said cone section in a circumferential spacing from the margin of said pipe opening; and said cone section lower end opening being spaced within said pipe below said pipe open end margin; a nipple merging from the upper side of and extending above said hemispherical section centered over the hemispherical section opening and the nipple having a top opening spaced above the hemispherical section.

BEN CONES.
